(57) **CLAIM**

The ornamental design for a chairlift seat with seat dividers,
as shown and described.

DESCRIPTION

FIG. 1 is a perspective view of a chairlift seat with seat dividers, showing my new design;

FIG. 2 is a side view thereof;

FIG. 3 is a top plan view thereof;

FIG. 4 is a rear view thereof; and,

FIG. 5 is a front elevation view thereof.

The broken lines showing a person on a chairlift seat is
included for the purpose of illustrating environment of the
design and forms no part of the claimed design.
